UNITED STATES PATENT OFFICE.

WILLIAM S. BIDLE, OF CLEVELAND, OHIO.

DESIGN FOR A WIRE-ROPE SOCKET.

SPECIFICATION forming part of Design No. 33,373, dated October 16, 1900.

Application filed August 27, 1900. Serial No. 28,263. Term of patent 14 years.

To all whom it may concern:

Be it known that I, WILLIAM S. BIDLE, a citizen of the United States, residing at Cleveland, in the county of Cuyahoga and State of Ohio, have invented and produced a new and original Design for Wire-Rope Sockets, of which the following is a specification, reference being had to the accompanying drawings, forming a part thereof.

- 5 • Referring to the drawings, Figures I and II are side elevations, taken at right angles to each other, of a wire-rope socket, showing my design. Figs. III and IV are opposite end elevations, respectively, of the socket. Fig. V is a section on line V V, Fig. I. Fig. VI is a section on line VI, Fig. I.

As shown in the drawings, one end portion 10 of the socket has the shape of a conical basket. The basket-shaped portion 10 is beveled annularly, as at 11, at its outer and smaller end. The other end portion 12 of the socket has the shape of a bail whose end members 13 and 13 extend from opposite sides, respectively, of the inner and larger end of the basket-shaped portion and are arranged parallel, and the central member 14 of the bail-shaped portion 12 is semicircular—that is, the central member 14 of the bail-shaped portion 12 curves inwardly from each end member 13 and is wider centrally than the end members 13. The member 14 gradually increases in width toward its central portion from the members 13. The external conical surrounding surface of the basket-shaped portion 10 of the socket is extended inwardly, as at 15, and forms the external surface of the inner ends of the end members 13 of the bail-shaped portion 12. The inner side of the bail-shaped portion has the shape required to form two continuous sloping surfaces 16 and 16, extending from the inner extremity of one of the members 13 along the said member 13, thence along the member 14, and thence along and to the inner extremity 5 of the other member 13. The said sloping surfaces 16 and 16 slope inwardly and toward

each other from opposite faces 17 and 17, respectively, of the bail-shaped portion 12 and meet centrally between the said faces. The external side of the bail-shaped portion of 50 the socket has the contour required to form two continuous sloping surfaces 18 and 18, extending from the inner extremity of one of the members 13 along the said member 13 to the member 14 and along the latter and along 55 the other member 13 to the inner extremity of the last-mentioned member. The sloping surfaces 18 and 18 slope outwardly and toward each other and meet centrally between the faces 17 and 17 of the bail-shaped portion. 60 The faces 17 of the bail-shaped portion of the socket are parallel at the central member 14 of the said portion, as shown at 19, Fig. II, but the sloping surfaces 16 and 18 gradually increase in width toward the basket-shaped portion of the socket. The basket-shaped portion has its inner end beveled or sloping somewhat, as at 20, from the faces 17 of the bail-shaped portion toward the external conical surface of the said basket-shaped 70 portion.

The leading or material feature of my design consists in the configuration of the bail-shaped portion of the socket and comprises, broadly, a parallel or approximately-parallel 75 arrangement of the end members of the said bail-shaped portion and the sloping surfaces 16 and 18, forming the inner side and the outer side, respectively, of the said bail-shaped portion.

Having described my invention, what I claim as new, and desire to secure by Letters Patent, is—

The design for a wire-rope socket, as herein shown and described. 85

Signed at Cleveland, Ohio, this 13th day of August, 1900.

WILLIAM S. BIDLE.
